UNITED STATES PATENT OFFICE

TALBERT M. DICK, OF DES MOINES, IOWA

FACE MASK OR LIKE

Application filed April 18, 1929. Serial No. 356,130.

The principal object of this invention is to provide a device that will stimulate blood circulation in the face, thereby eliminating impurities in the skin and giving to the face a normal healthy appearance.

A further object of this invention is to provide an electrically heated face mask capable of causing the face to perspire, thereby opening up the pores in the skin and 10 cleaning the same of undesirable foreign matter and poisons.

A still further object of this invention is to provide a device that stimulates and strengthens the facial cells and muscles and 15 clears the blood channels of congestion.

A still further object is to provide a skin treating device that provides an even, uniform, continuous heat.

A still further object of my invention is to 20 provide an electric face mask that is light in weight and sanitary.

A still further object of the invention is to provide an electrically heated mask that is capable of embracing the face and neck of 25 the user.

A still further object of this invention is to provide an electrically heated face mask that is flexible and capable of conforming to the face outline of various people.

A still further object of my invention is to 30 provide an electrically heated face mask that is easily and readily attached to or detached from the face and neck of the user.

A still further object of this invention is to 35 provide an electric face mask that is economical in manufacture, durable and safe in use, and refined in appearance.

These and other objects will be apparent to those skilled in the art.

40 My invention consists in the construction, arrangement and combination of the various parts of the device, whereby the objects contemplated are attained as hereinafter more fully set forth, pointed out in my claims and illustrated in the accompanying drawings, in which:

Fig. 1 is a front view of my invention ready for use.

45 Fig. 2 is a side view of the invention illustrating the manner in which the mask and

neck band embrace the face and neck of the user.

Fig. 3 is a diagrammatical view of the electric wiring of the device.

Fig. 4 is a cross sectional view taken on line 4—4 of the neck band and shows the manner in which the electric wiring is embedded in the same.

It is well known that unhealthy facial skin, evidenced by sallowness, blackheads, enlarged pores, skin eruptions, creases, etc. is principally caused by improper blood circulation. It is also well known that heat and electric currents subjected to the skin stimulate blood circulation. The most popular methods of today for stimulating blood circulation in the face are hot wet towels applied to the skin, and massage. The chief objection to steamed towels is their inability to cause the face to perspire, unevenness of 70 temperature, and untidiness in use.

Massaging of the skin does stimulate the same to some extent, but great care must be exercised or small cells and tissues will be broken. Neither of the methods, however, 75 safely stimulate the skin and remove waste matter therefrom. I have overcome these objections by providing a safe, sanitary electrically heated stimulating mask.

I have used the numeral 10 to designate 80 the face portion of the mask and the numeral 11 to designate the neck embracing portion. This face and neck portion is preferably molded of suitable air-tight flexible and elastic material such as rubber or the like and 85 may have a heat insulating core 12, of sponge rubber as shown by the cross-sectional view of Fig. 4. Embedded in the face and neck portion of the mask is a circuit of resistance wire 13 extending in spaced convolutions 90 throughout the area of the face and neck portions and which has its length of coil construction wound around a cord 14 of asbestos or like flexible material. By this arrangement of parts the convolutions will not only be completely surrounded by the rubber portion of 95 the invention but will be held apart one from the other. This wire should be of such diameter and length as to produce, when in electrical communication with a source of 100

electric energy of 110 volts, approximately 110 degrees Fahrenheit adjacent to the inner side of the face and neck portions. By the mask being constructed of rubber and the 5 wiring of coil construction, the invention will be very flexible and elastic and although formed to fit the average human face, it will readily conform itself to fit various sizes and outlines of faces. Openings (not numbered) 10 may be formed in the face portion for accommodation of the eyes and nose of the wearer. I have used the numeral 15 to designate electric cord making contact with the electric wire in the invention and designed 15 to be placed in contact with a source of electric energy. The numeral 16 designates the usual switch in the cord 15 for making and breaking the electric circuit. The face portion of the device is detachably held on the 20 face of the user by elastic embracing bands 17 shown in Fig. 2, thereby making the invention easily placed on or removed from the face.

The neck portion 11 may be detachably and 25 adjustably secured around the neck of the user by any suitable means. In the drawings I show this accomplished by a plurality of common snap-fasteners 18. By such a construction, the neck portion will fit any size 30 of neck. The numeral 19 designates a bead formed on the marginal edge of the face portion for strengthening the same and causing the mask to fit the face very snugly at the outer edge of the same, thereby aiding in 35 holding the hot air and heat adjacent to the face until the mask is removed.

After the mask is on the face and neck of the user for approximately seven minutes, the face and neck will start to perspire. This 40 will cause the pores of the skin to expand and the perspiration will act as a vehicle for carrying toxic poisons and waste matter out of the skin. This action is just the opposite from the hot towel method which drives the heat 45 in. The heat from the invention will be even, constant, and uniform, thereby causing the blood circulation in the skin to function in a normal manner. This will eliminate congested blood channels and strengthen and 50 stimulate all the facial cells and tissues.

With the prevalent use of cosmetics that enter and harden in the pores of the skin, the use of such a device is imperative.

A facial and neck treatment with my invention should cover a period of about fifteen to twenty minutes. After removing the device from the face of the user, the skin so treated should be bathed in cool water to close the skin pores and it will be found upon inspection that the skin will then have a clean, healthy and normal appearance.

As the invention is made of smooth rubber, the same may easily be washed and kept clean.

65 Some changes may be made in the con-

struction and arrangement of my improved electrically heated stimulative face mask and neck band, without departing from the real spirit and purpose of my invention and it is my intention to cover by my claims any modified forms of structure or use of mechanical equivalents which may be reasonably included within their scope. 70

I claim:

1. As a new article of manufacture, a flexible rubber pad like body adapted to embrace the face of the user, and an electric circuit of resistance wire embedded in said rubber, said wire being arranged in convolutions through the area of said body. 75

2. As a new article of manufacture, an elastic face embracing member, and a metallic member embedded in said embracing member capable of transforming electrical energy into heat, said metallic member having portions thereof distributed throughout the area of the elastic face embracing member. 85

3. As a new article of manufacture, a flexible rubber sheet member designed to embrace the face of the user, an enlarged bead formed on the marginal edge of said sheet member, and an electric circuit of resistance wire embedded in said sheet member, said wire being arranged in convolutions throughout the area of said rubber sheet member. 90

4. As a new article of manufacture, a flexible rubber sheet member designed to embrace the face of the user, a cord embedded in said sheet member of non-conductive material and a metallic wire wound around said cord and designed to be in electrical communication with a source of electric energy, said cord being arranged in convolutions throughout the area of said rubber sheet 100 member. 105

5. As a new article of manufacture, a flexible rubber face embracing portion, a neck embracing portion integrally formed on said face embracing portion, and a circuit of electrical resistance wire embedded in said face and neck embracing portions, said wire being arranged in convolutions throughout the area of said face and neck embracing portions. 110

6. As a new article of manufacture, a flexible rubber face embracing portion, a means for detachably securing said face embracing portion to the face of the user, a neck embracing portion integrally formed on said face embracing portion, a means for adjustably securing said neck embracing portion around the neck of the user, and a circuit of electrical resistance wire embedded in said face and neck embracing portions, said wire being arranged in convolutions throughout the area of said face and neck embracing portions. 120 125

7. In a device of the class described, a flexible rubber face embracing portion molded 130

to conform to the general outlines of the face of a human being, a flexible band for securing said face embracing portion to the face of the user, a flexible rubber neck embracing portion integrally formed on the lower end portion of the face embracing portion, a means for adjustably securing said neck embracing portion around necks of various sizes, and a circuit of heat producing electrical resistance wire embedded in said face and neck portions, said wire being arranged in convolutions throughout the area of said face and neck embracing portions.

8. As a new article of manufacture, a pad-like body adapted to engage the face, a sponge rubber ply comprising the central portion of said body, a metallic heat generating unit embedded in said sponge rubber ply, and sheets of rubber secured to the opposite surfaces of said sponge rubber ply, said heat generating unit having portions thereof distributed throughout the area of the body.

9. As a new article of manufacture, a flexible rubber pad like body adapted to engage the face of the user, and an electric circuit of resistance wire embedded in said rubber and arranged in spaced convolutions throughout the area of said body; said convolutions being supported and held in spaced relationship solely by the surrounding material of said body.
